US00D925354S

(12) **United States Design Patent** (10) Patent No.: **US D925,354 S**
(45) Date of Patent: **** Jul. 20, 2021**

(54) **SPICE CONTAINER**

(71) Applicant: **MCCORMICK & COMPANY, INCORPORATED**, Hunt Valley, MD (US)

(72) Inventors: **Tracie L. C. Wilson**, Westminster, MD (US); **Don Ankney**, Stanford, KY (US); **Ron Myers**, Jackson, TN (US)

(73) Assignee: **MCCORMICK & COMPANY, INCORPORATED**, Hunt Valley, MD (US)

(**) Term: **15 Years**

(21) Appl. No.: **29/677,144**

(22) Filed: **Jan. 17, 2019**

Related U.S. Application Data

(62) Division of application No. 29/578,133, filed on Sep. 19, 2016, now Pat. No. Des. 845,139.

(57) **CLAIM**

We claim the ornamental design for a spice container, as shown and described.

DESCRIPTION

FIG. 1 is a front elevation view of a spice container showing our new design;

FIG. 2 is a rear elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines in the drawings showing the spice container illustrate the portions of the spice container that form no part of the claimed design.

1 Claim, 6 Drawing Sheets
